CLAIM

The ornamental design for a grill tool handle as shown and described.

DESCRIPTION

FIG. 1 is an elevational top-side view of a grill tool handle, in accordance with the present invention;

FIG. 2 is an elevational right-side view of the grill tool handle of FIG. 1;

FIG. 3 is an elevational bottom-side view of the grill tool handle of FIG. 1;

FIG. 4 is an elevational left-side view of the grill tool handle of FIG. 1

FIG. 5 is a front elevational view thereof;

FIG. 6 is a back/rear elevational view thereof; and,

FIG. 7 is a perspective view of the grill tool handle of FIG. 1.

The broken lines are shown for the purpose of illustrating environmental subject matter of an exemplary grill tool and form no part of the claimed design.

1 Claim, 6 Drawing Sheets
